UNITED STATES PATENT OFFICE

ALBERT EDWARD LEEK, OF WIGAN, ENGLAND

HEAT-EXCHANGE APPARATUS

Application filed May 6, 1926, Serial No. 107,230, and in Great Britain September 18, 1925.

This invention relates to heat exchange apparatus and has for its object to provide an improved construction and arrangement of the economizer or heater as employed for water heating purposes, to adapt it also for the efficient pre-heating of air, required, for example, for combustion in the generator furnace or furnaces.

The invention comprises a combined air and water heater for steam generating plant consisting of the combination of nested tubes or ducts and an enclosing casing or enclosing tubes such that intermediate ducts are provided through which the hot gases flow, the latter contacting with the exterior surface of the inner units and the interior surface of the outer units of said nested tubes or ducts.

Referring to the accompanying explanatory drawings:—

Figure 1 is a sectional elevation showing, in diagrammatic form one manner of carrying the invention into effect.

Figure 2 is a sectional end view showing one arrangement of the tubes or ducts of my improved economizer or feed water heater and Figure 3 a similar view showing another arrangement.

Figure 4 is a sectional view in diagrammatic form showing another manner of carrying the invention into effect.

The same reference letters in the different views indicate the same or similar parts.

As is illustrated at Figures 1 and 2, the water tubes *a* (of which only four are shown in Figure 1) extending between headers as *b* of the economizer or feed water heater, are each provided with an outer tube *c* extending between the end plates *d* of a casing *e*. The hot gaseous products admitted at *f* flow through the spaces between the said nested tubes *a* and *c*, passing from *f* through the said spaces in the lower half of the casing *e* and returning through those in the upper half to the outlet at *g*. Such flow of the hot gases is indicated by the arrows 1 at Figure 1.

The air to be heated is admitted at *h* to the casing *c* which is fitted with a baffle or division plate *i* such that the air after passing through the spaces between the respective

outer tubes *c* in the upper half of the casing, returns through the like spaces in the lower half to the outlet at *j*. Such flow of the air, which is in a counter direction to the flow of the hot gases, is indicated by the arrows 2 at Figure 1.

The water flows through one set of tubes *a* and returns through the other set. It may be passed through one set of tubes only or through more than two sets to suit requirements.

The hot gases may also be circulated back and forth many times over the water tubes. The air also may be heated in several stages or in a single stage as desired.

The casing *e* may be of a circular, or of a rectangular, square or other section to meet requirements. The casing shown at Figure 2 is circular and has filling pieces *k* which form dead air spaces to deflect the air from the side of the casing and keep it in close contact with the tubes *c*.

In the example illustrated at Figure 3, a row of water tubes *a* is enclosed by one outer tube or duct *c* of a rectangular section. As in the previous example, the hot gases flow through the spaces between the exterior of the water tubes and the interior of the enclosing tubes or ducts *c*, whilst the air flows in the spaces, as 1, between the exterior surfaces of the said ducts *c*. The latter may be corrugated and the tubes placed in a staggered formation.

In the arrangement shown in Figure 4, the air is passed through tubes *m*, each of which encloses concentric hot gas and water tubes *c* and *a* respectively. The separate tubes may be connected to headers as shown. Or the arrangement may be such as to cause the air and water to be heated in several stages: a single stage heating as shown may however be utilized.

Suitably curved deflecting surfaces are provided for the respective changes of direction of the gases and of the air with a view to the maintenance of the velocity of flow.

The surfaces of the tubes exposed to the hot gaseous products of combustion can be cleaned by the aid, for example, of steam jets in the known manner.

What I claim is:—

A combined air, water and flue-gas heat interchanger comprising in combination a circular casing, end plates spaced from the ends of said casing, pairs of tubes arranged concentrically one within the other between said end plates and arranged in quincunx, means for passing flue gas through the annular passage between said tubes which are arranged so that the gas flows in double pass, means for passing water through the inner tubes and means for passing air over the outer surfaces of said tubes such that the air and water flow in double pass and in contra flow to the movement of the flue gas from which heat is extracted, and flat, longitudinal, segmental plates arranged within said casing, each plate being parallel in cross sectional view to a line through the axes of the nearest row of tubes, so as to restrict the passage of air through the apparatus and to avoid dead spaces.

In testimony whereof I have signed my name to this specification.

ALBERT EDWARD LEEK.
